(57) **CLAIM**

The ornamental design for a tamper resistant spore trap, as
shown and described.

DESCRIPTION

FIG. 1 is a front, right, perspective view showing my new
design;

FIG. 2 is a rear, right perspective view thereof;

FIG. 3 is a front side view thereof;

FIG. 4 is a rear side view thereof;

FIG. 5 is a side view thereof;

FIG. 6 is a front, left, perspective view thereof; and,

FIG. 7 is a rear, left, perspective view thereof.

The broken lines illustrate portions of the tamper resistant
spore trap and form no part of the claimed design.
